United States Patent [19]

Lalley

[11] Patent Number: Des. 297,715

[45] Date of Patent: ** Sep. 20, 1988

[54] INDUCTIVE AMPLIFIER

[75] Inventor: Donald P. Lalley, Tempe, Ariz.

[73] Assignee: Progressive Electronics, Inc., Mesa, Ariz.

[**] Term: 14 Years

[21] Appl. No.: 812,387

[22] Filed: Dec. 23, 1985

[52] U.S. Cl. D10/78; D10/103

[58] Field of Search ..... D10/75, 78, 103; 324/73 PC, 72.5, 61 P, 234, 262, 73 R, 149, 156; 439/482

[57] CLAIM

The ornamental design for an inductive amplifier, as shown.

DESCRIPTION

FIG. 1 is a front and top-left perspective view of an inductive amplifier showing my new design;

FIG. 2 is a top plan view thereof;

FIG. 3 is a bottom plan view thereof;

FIG. 4 is a right side elevational view thereof;

FIG. 5 is a rear elevational view thereof;

FIG. 6 is a front elevational view thereof.
